UNITED STATES PATENT OFFICE.

JOHN B. LACY, OF CHICAGO, ILLINOIS.

REFRIGERATOR.

1,271,482.

Specification of Letters Patent.

Patented July 2, 1918.

Application filed July 9, 1917. Serial No. 179,531.

To all whom it may concern:

Be it known that I, JOHN B. LACY, a subject of the King of England, residing at Chicago, county of Cook, State of Illinois, have invented a certain new and useful Improvement in Refrigerators, and declare the following to be a full, clear, and exact description of the same, such as will enable others skilled in the art to which it pertains to make and use the same, reference being had to the accompanying drawings, which form a part of this specification.

In no refrigerator or refrigerating room of which I am aware, although various expedients have been suggested or adopted, is there an efficient circulation of air unless produced by a fan or blower or other mechanical means.

The object of the present invention is to produce a simple and novel construction and arrangement of parts which will insure a positive strong circulation of air in such a way as not only to keep the temperature in the storage compartment at a lower temperature than would otherwise be possible, but to produce this result with a smaller consumption of ice or a smaller consumption of energy where mechanical refrigeration is employed.

It follows from an effective circulation that the walls of the storage compartment and the things stored in such compartment will remain dry through the prevention of condensation and it also follows that the air in the storage compartment will be automatically purified in much the same way as where it is passed through an air washer and therefore, viewed in one of its aspects, my invention may be said to have for its object to produce a simple and novel structure by means of which dry pure air will automatically be maintained in the storage compartment of a refrigerator or refrigerating room.

In carrying out my invention, a few simple structural elements which may be applied to any refrigerator or refrigerating room are employed and therefore, regarded in one of its aspects, my invention may be said to have for its object to produce a simple means which may readily be applied to an existing refrigerator or refrigerating room for the purpose of economizing in ice or refrigerating energy, insuring dryness of the air in the storage compartment and auto-

matically maintaining the air in such compartment pure.

The various features of novelty whereby my invention is characterized will herein-after be pointed out with particularity in the claims; but, for a full understanding of my invention and of its objects and advantages, reference may be had to the following detailed description taken in connection with the accompanying drawings, 65 wherein:

Figure 1 is a vertical section through a refrigerating room or refrigerator embodying my invention in a structure wherein there are a plurality of cold air flues remote 70 from each other;

Fig. 2 is a view similar to Fig. 1, showing a modified arrangement in which the cooling chamber lies between two storage chambers;

Fig. 3 is a view similar to Fig. 1, showing a reversal of the flues, there being a cold air flue at the center and warm air flues at the sides;

Fig. 4 is a view similar to Fig. 1, showing a still further modification in which there is a cooling chamber lying beside a storage chamber; and

Fig. 5 is a view similar to Fig. 4, showing a structure of the same character as Fig. 4, 85 but adapted to employ cold pipes instead of ice as the cooling means.

I have discovered that if the storage compartment and the compartment for the cooling means in a refrigerating room or refrigerator to which I shall refer simply by the general name refrigerator, are connected together by means of flues which will permit the cold air to flow freely and in large volume directly into the bottom of the storage compartment while confining and controlling the entrance of the air from the top of the storage compartment into the top of the other compartment in the form of a comparatively thin sheet, thus causing the 100 cold air gradually to bank up on the bottom of the storage compartment and rise in the latter toward the top, taking up heat units on the way up, the air is forced into the compartment for the cooling means under an appreciable pressure and therefore travels at a comparatively high velocity so as to bring about the condition of a comparatively thin sheet or layer of air coming in contact with the cooling medium while travel- 110

ing at a high speed. The results are: first, that rapid condensation of moisture takes place in the chamber containing the cooling means, which condensation is precipitated and is drained off, avoiding entirely the formation of fog which is produced in the ordinary refrigerator when large volumes of air, slow and vacillating in their movements, come in contact with the cooling medium, and the cool air entering the storage compartment is therefore comparatively dry; second, that the air in the storage chamber circulates much more rapidly than has heretofore been thought possible without the use of fans or blowers. The avoidance of fog, and the rapid and positive circulation of the air, produce a minimum temperature in the storage compartment for a given consumption of ice or energy in other form or, in other words, insure a lower temperature in the ordinary refrigerator for a given consumption of ice or even a lesser consumption than has heretofore been required to maintain a higher temperature in the storage compartment, prevent condensation of moisture in the storage chamber, and insure rapid and automatic purification of the air through what is substantially a washing process so that the air in the storage compartment will be very quickly purified if contaminated through the entrance of foul air through an opened door or because of contamination from tainted food or the like placed in the storage chamber.

Referring to Fig. 1 of the drawings, 1 represents a chamber having heat insulated walls. The chamber is divided into a lower storage compartment, 2, and an upper compartment, 3, for the cooling means which may take the form of ice or cooling coils. The wall, 4, separating the two compartments is insulated so that the air flowing along the same in the lower compartment will not be cooled and drop down without being required to pass through the cooling compartment. At the center of the wall, 4, is a rising flue, 5, which is funnel shaped, being wider at the bottom than at the top so that the side walls, 8, converge toward each other from their lower ends toward their upper ends; the length of the flue at right angles to the plane of the paper being equal to the length of the two compartments of the chamber. At its upper end the flue is provided with laterally projecting branches, 6, each opening into one side or the other of the compartment 3. The flues, 6, like the main flue 5, decrease gradually in cross sectional area so that the combined area of their outlet ends is much less than the area of the inlet end of the flue 5. The upper sides of the flue 6 are formed by the ceiling or roof of the chamber which preferably rises gradually from the extreme cen-

ter to the sides of the chamber. The ceiling or roof of an ordinary refrigerator may be given the proper shape by simply attaching thereto a false ceiling, 7, triangular in vertical cross section. At each side of the refrigerator is a downwardly extending flue, 9, which extends from the bottom of the upper chamber to a point adjacent to the bottom of the lower chamber. The combined cross sectional areas of the flues 9 is made greater than and preferably much greater than the combined areas of the small ends of the flues 6. In actual practice I have found that the best results are obtained when the cross sectional area of the small ends of the flues 6 is about thirty per cent. of the cross sectional area of the flues 9.

With the arrangement just described, ice or any other cooling means being arranged within the chamber 3, the cold air will descend freely and in large volume through the flues 9 into the very bottom of the storage chamber. As the cold air enters the storage chamber it begins to take up heat units and rises, additional cold air forcing its way underneath the same, until finally the warmed air reaches the flue 5 and rises through the same. Because of the flue 5 and its continuations, the flues 6 offer a more and more contracted outlet for the passage of the rising air, an appreciable pressure is produced in the ascending flue and the air finally rushes into the two halves of the chamber 3 in the form of thin layers traveling along the ceiling. The action in the upper chamber is just the reverse from what takes place in the lower chamber, the warm air entering the top of the upper chamber being quickly chilled by the air already present in that chamber, and dropping down until it comes in contact with the ice or other cooling means until finally the flues 9 are reached.

After the air has once been set in motion, there is no opportunity given it for vacillating or reversing its direction, but it must keep on circulating as long as there is a cooling means present. I have found that the air in the storage compartment will circulate at a rate of thirty linear feet per minute while at the point of entry into the upper chamber, the speed will be as high as one hundred feet a minute. The air being comparatively dry and the walls 4 and 8 being insulated, no condensation of moisture in the storage chamber can take place, all condensation being effected in the upper chamber and being carried away by means of troughs, 10, or other suitable means.

In Fig. 2 the chamber 11 is divided into two storage compartments, 12 and 13, separated from each other by a central compartment, 14, for the cooling means. The side walls, 15, of the compartment 14 are insulated. The lower end of the compartment 14 terminates in a descending or cold

air flue, 16, which terminates a short distance above the floor of the refrigerator so that the descending cold air divides into two streams one of which enters the compartment 12 and the other the compartment 13. A flue, 17, extending inwardly from one of the side walls of the compartment 14 connects the latter compartment with the compartment 12, while a similar flue, 18, connects the compartment 14 together with the compartment 13. The ceiling, 19, in this case, is gradually inclined upwardly from the sides of the refrigerator toward the middle.

In Fig. 3 the arrangement is very similar to that shown in Fig. 1 except that the descending or cold air flue, 20, is placed at the center of the chamber 21 and the ascending or warm air flues, 22 and 23, are placed at the sides. The flues 22 and 23 terminate in lateral extensions or continuations, 24 and 25, respectively, these corresponding in position and function to the flues 6 in Fig. 1.

In Fig. 4 I have shown an arrangement in which the refrigerator, 26, is divided into a storage compartment, 27, and a compartment, 28, for the cooling means arranged side by side and separated by an insulated wall, 29. The ceiling, 30, of the storage compartment is inclined upwardly as the compartment 28 is approached and forms an inclined top for a warm air flue, 31, extending inwardly across the top of the compartment 28 from the wall 29. The bottom of the compartment 28 is open, as indicated at 32, at a short distance above the bottom of the refrigerator, so that the chilled air flows into the storage compartment at the bottom of the latter.

While the arrangement shown in Fig. 4 is one adapted to employ either ice or cooling coils, in Fig. 5 I have illustrated an arrangement wherein, because of limited space, the cooling compartment cannot be made very large and cooling pipes, instead of ice, must be employed. Referring to Fig. 5, 33 and 34 are the storage compartment and the cooling compartment arranged side by side and separated from each other by an insulated wall, 35, which terminates a short distance above the bottom of the refrigerator 36. The upper end of the wall 35 is extended laterally, as indicated at 37, over the top of the adjacent portion of the storage compartment. A flue, 38, extends inwardly from the outer or free end of the wall 37, this flue being of the same type and having the same characteristics as the other ascending or warm air flues heretofore described. The ceiling, 39, of the refrigerator is inclined upwardly from the side opposite that at which the cooling compartment 34 is located. This arrangement forms an enlargement, 40, at the top of the chamber 34 and therefore provides a larger cross sectional

area in which the cold air in the cooling compartment may act on the rapidly incoming sheet or layer of warm air.

There is another advantage that results from the use of my improvements to which I have not heretofore referred and that is that the space required for the compartment for the ice or other cooling means is much less than that in the old types of refrigerators, there being frequently a saving of more than a third in the space employed for this purpose. In the case of old refrigerators to which my improvements are applied, this means a material enlargement of the storage compartment or chamber.

In addition to the employment of my improvements for purely refrigerating purposes, wherever it may be desired to have refrigeration, my invention is also applicable to the cooling and purifying of the air in any substantially air-tight compartment used for any purpose; and, where I use the term storage compartment, I intend to cover any substantially air-tight compartment in which the air is to be cooled and purified or simply purified.

I claim:

1. A chamber divided into a storage compartment and a compartment for a cooling means, a cold air flue of large cross sectional area leading from the bottom of the second compartment to a point a short distance above the bottom of the storage compartment, and there being a warm air flue of large cross sectional area at its inlet end leading from the upper portion of the storage compartment into the upper portion of the other compartment, said warm air flue having its extreme upper end so disposed that the air discharged therefrom is delivered directly into the cooling compartment in a substantially horizontal direction, and the said warm air flue decreasing gradually in cross sectional area until at its outlet end it is so restricted that the air is discharged in a broad thin sheet.

2. A chamber divided into a storage compartment and a compartment for a cooling means, a cold air flue of large cross sectional area leading from the bottom of the second compartment to a point a short distance above the bottom of the storage compartment, and there being a warm air flue of a length considerably greater than its height extending in an approximately horizontal direction from the upper portion of the storage compartment into the upper portion of the other compartment, said warm air flue being of comparatively large cross sectional area at its inlet end and decreasing in cross sectional area toward its outlet end so that the outlet end is sufficiently restricted to cause the air to be discharged in a broad thin horizontally directed sheet.

3. A chamber divided into a storage com-

partment and a compartment for containing a cooling means, a warm air flue connecting the upper regions of said compartments together and decreasing gradually in cross sectional area from the storage compartment end toward the other end, the top wall of the outlet end of the aforesaid flue being inclined upwardly from the inlet end of the flue toward the outlet end, and a cold air flue extending from a point near the bottom of the storage compartment to the bottom of the other compartment.

4. A chamber divided into a storage compartment and a compartment for containing a cooling means, a warm air flue connecting the upper regions of said compartments together and decreasing gradually in cross sectional area from the storage compartment end toward the other end, the top wall of said warm air flue rising from the inlet end of the flue to the outlet end and joining the upper wall of the cooling compartment, the latter wall also rising as the distance from the outlet end of the warm air flue increases, and a cold air flue extending from a point near the bottom of the storage compartment to the bottom of the other compartment.

5. A chamber divided into a storage compartment and a compartment for containing a cooling means, a warm air flue connecting

the upper regions of said compartments together and decreasing gradually in cross sectional area from the storage compartment end toward the other end, both the bottom and the top walls of said warm air flue rising from the inlet end of the flue toward the outlet end, and a cold air flue extending from a point near the bottom of the storage compartment to the bottom of the other compartment.

6. A chamber divided into a storage compartment and a compartment for containing a cooling means, a warm air flue connecting the upper regions of said compartments together, the ceiling or upper wall of said chamber rising gradually from the side of the storage compartment remote from the other compartment to the opposite side of the chamber forming the top of the cooling compartment, said inclined ceiling forming the top wall of said warm air flue, the bottom wall of the warm air flue being also inclined upwardly from the inlet end of the flue to the outlet end, and a cold air flue extending from the bottom of the storage compartment to the bottom of the cooling compartment.

In testimony whereof, I sign this specification.

JOHN B. LACY.
